UNITED STATES PATENT OFFICE.

GUSTAV T. E. HENRIKSEN, OF CHICAGO, ILLINOIS.

OILING DEVICE FOR STOCKS AND DIES.

969,867.

Specification of Letters Patent. Patented Sept. 13, 1910.

Application filed August 5, 1907. Serial No. 387,073.

To all whom it may concern:

Be it known that I, GUSTAV T. E. HENRIKSEN, a citizen of the United States, residing at Chicago, in the county of Cook and State of Illinois, have invented a certain new and useful Improvement in Oiling Devices for Stocks and Dies, of which the following is a specification.

This invention relates to devices for forming screw threads, and has for its object to provide a new and improved device of this description.

The invention is illustrated in the accompanying drawings, wherein—

Figure 1 is a view in part section showing one form of device embodying the invention; Fig. 2 is a section on line 2—2 of Fig. 1; Fig. 3 is a view showing a modified construction.

Like letters refer to like parts throughout the several figures.

In forming screw threads with a stock and die, for example, it is necessary to apply oil at the point where the die engages the part upon which the screw threads are formed. It is difficult and inconvenient to apply this oil under the ordinary conditions.

One of the objects of my invention is to provide a construction whereby this oil is applied conveniently at the proper times and in proper amounts.

Referring now to Fig. 1, I have shown a stock A provided with a die B with a piece of pipe C in position and upon which threads are being made. The handle-piece D for the stock or holder of the die is hollow and is preferably filled or partially filled with oil. Within this handle is a reciprocating part E which is held in place in any desired manner, as by means of the guides F. These guides preferably fit the reciprocating part E so as to make an oil-tight joint. A shoulder G is attached to, or formed on, the part E and a spring H is located between this shoulder and the guide F. The reciprocating part E is provided with one or more openings I above the guide F, and one or more openings J which are normally opposite the guide F but arranged so that when the guide is moved in the direction of its length one opening will pass below the guide so that the oil may escape, the passage being from the handle D through the openings F and J. A stop K is attached to the reciprocating part E so as to limit its movement under the tension

of the spring H. The escaping oil passes into the chamber L and thence through the conductor M to the point where the threads of the die engage the device acted upon. It will thus be seen that the operator by occasionally pushing on the reciprocating part E can apply the oil directly to the point of use.

As illustrated in Fig. 3, the guide F is provided with one or more openings F¹. The reciprocating part E is provided with a valve device F² which closes said opening or openings by means of the pressure of the spring H. A washer or packing F³ may be used if desired to insure a proper joint. When the reciprocating device E is moved it opens up the openings F¹ and permits the oil to escape. It will be seen that by this construction the oil can be easily applied at the proper point, and that hence less oil is wasted and the application of a proper amount of oil is insured. It will further be noted that when the reciprocating part is moved the shoulder G tends to compress the oil between it and the guide F, thus tending to force the oil out and secure a proper flow thereof.

I claim:

1. An oiling device for a stock and die comprising a hollow handle connected with the stock, and adapted to contain a liquid, a reciprocating part within said handle and extending therewith, two guides in said hollow handle separated from each other, both having holes therein just large enough for the reciprocating part to pass therethrough said reciprocating part passing through both of said guides and fitting tightly therein so as to normally prevent the escape of the liquid through the guides, but free to reciprocate, the guides acting as confining parts between which the liquid is contained, a spring located in the space between said guides and surrounding a portion of said reciprocating part, one end of said spring engaging one of said guides, and the other end said reciprocating part and means for releasing a portion of said liquid by a longitudinal movement of said reciprocating part.

2. An oiling device for a stock and die comprising a hollow handle connected with the stock, and adapted to contain a liquid, a reciprocating part within said handle and extending therewith, two guides in said hollow handle separated from each other,

- 1 said reciprocating part passing through both of said guides and fitting tightly therein so as to normally prevent the escape of the liquid through the guides, but free to 5 reciprocate, the guides acting as confining parts between which the liquid is contained, and means for releasing a portion of said liquid by a longitudinal movement of said reciprocating part, and a compressing device for forcing the liquid out of said handle when the reciprocating device is moved comprising an enlargement on said reciprocating part in proximity to the guide through which the liquid escapes. 10
- 15 3. An oiling device for a stock and die comprising a hollow handle connected with the stock and adapted to contain oil, two guides at a distance from each other located within said hollow handle, a reciprocating part passing through both of said guides and fitting tightly therein so as to prevent the oil from escaping between the engaging faces of the guides and said reciprocating part, and means for releasing a 20 portion of said oil when said reciprocating part is moved, said oil escaping through one of said guides, a chamber below the end of said hollow handle into which said oil is received, and a pipe at one side of said 25 chamber connecting with said chamber near the back thereof, and having a curved end which discharges the oil at the point of use. 30
- 35 4. An oiling device for a stock and die comprising a hollow handle connected with the stock, two guides within said hollow handle forming between them a liquid chamber, a reciprocating part passing
- through both of said guides and projecting at each end beyond them, a spring associated with said reciprocating part and located between said guides and within the oil chamber, the opening through which the liquid escapes from said chamber being beyond said spring so that the liquid passes the spring before escaping from the chamber said spring adapted to move the reciprocating part to its initial position, and means for permitting the escape of the oil when the reciprocating part is moved. 40
- 45
5. An oiling device for a stock and die comprising a hollow handle connected with the stock and adapted to contain liquid, two guides in said hollow handle separated from each other and forming a liquid chamber between them, a reciprocating part passing through openings in said guides so as to fit tightly therein and prevent the escape of oil between the engaging faces of the reciprocating part and the guides, a passageway through said reciprocating part and communicating with the space between the guides and having its exit end opposite one of said guides so as to be closed thereby when the reciprocating part is in its normal position, means for moving said reciprocating part so that the exit end of said passageway moves beyond the guide to permit the escape of the liquid from the liquid chamber. 50
